UNITED STATES PATENT OFFICE.

AXEL S. VOGT, OF ALTOONA, PENNSYLVANIA.

TRUCK-FRAME FOR RAILWAY-CARS.

SPECIFICATION forming part of Letters Patent No. 587,886, dated August 10, 1897.

Application filed April 1, 1897. Serial No. 630,241. (No model.)

To all whom it may concern:

Be it known that I, AXEL S. VOGT, a subject of the King of Sweden and Norway, residing at Altoona, in the county of Blair and 5 State of Pennsylvania, have invented a certain new and useful Improvement in Truck-Frames for Railway-Cars, of which the following is a full, clear, and exact description.

This invention relates to that form of railway-car trucks commonly known as "diamond" trucks.

In diamond trucks as ordinarily constructed the arch-bars, which constitute parts of the side or side frames, are made of rolled 15 bars of rectangular cross-section having their ends meeting above the journal-boxes, the arch-bars diverging midway, the upper arch-bar resting upon the transom and the lower arch-bar passed under the spring-plank, a 20 pedestal tie-bar or box-stay of similar cross-section extending from one pedestal to the other and these several bars being united centrally by vertical bolts and also being united at the pedestals or about the journal-boxes by vertical bolts. There are some 25 faults incident to this structure. For example, there is a general lack of rigidity in a vertical plane because of insufficient provision for uniting the arch-bars at the ends, 30 the main strain being thrown upon the bolts, and thus the principal of construction—namely, a truss—being to that extent defeated. There is also a lack of rigidity in a horizontal plane, because the arch-bars on opposite 35 sides of the truck are inadequately united to the transoms, the result being that the truck does not retain its original shape—that is to say, it gets out of square—with the result that there is excessive wear of journals, journal-bearings, and wheel-flanges and often-times an excessive heating of the journal-boxes. Furthermore, the structure lacks adaptability to varying conditions of track. 40 For example, where the four points of contact of the wheels with the rails are not in the same plane the strain is unevenly distributed. It is the object of my invention to avoid these and other faults which exist in the construction of the common diamond 45 truck-frame.

In my invention the arch-bars in the preferred form are made of channel-bars of

pressed steel with their ends inserted one within the other and riveted together, the flanges preventing lateral displacement and 55 the rivets preventing longitudinal and vertical displacement, thus forming a perfect truss. Again, these arch-bars, instead of being of uniform width, as in the ordinary diamond truck, are of gradually-increasing width 60 from their outer ends toward their centers, and they are riveted to the transom, thus obtaining an enormous increase of strength and of resistance to lateral distortion, so as to avoid the possibility of the truck getting out 65 of square. The transom which connects the side frames is also of channel form, and in order to increase its flexibility and thus to give to the truck structure the greatest possible chance to adapt itself to variations in 70 the track-surface it has a large portion of its vertical webs removed at points where its presence is not necessary for strength. The channel-beams of the transom have their ends boxed in, so as to stiffen them and there- 75 by afford a support for the lower arch-bar.

The bolster consists, essentially, of two channel-shaped members of variable depth, the webs standing vertically and the two channels being tied together, the greatest 80 depth being at the center and tapering thence to the ends, so as to afford ample room for the reception of the springs, which springs are supported upon spring-hangers which depend from the transom. The devices used 85 for tying together the members of the bolster at their ends are themselves peculiar and require peculiar flanging of the bolster, having in view the necessity of meeting eccentric loads and for other purposes. 90

Having thus stated the principle of my invention, I will proceed now to describe the best mode in which I have contemplated applying that principle, and then will particularly point out and distinctly claim the parts, 95 combinations, and improvements which I claim as my invention.

In the accompanying drawings, illustrating my invention, in the several figures of which like parts are similarly designated, Figure 1 100 is a half top plan view and horizontal section of half of the truck. Fig. 2 is a half elevation and vertical section of the same. Fig. 3 is a section taken in the plane of line 3 3,

Figs. 1 and 2. Fig. 4 is a half end view and vertical section. Fig. 5 is a vertical section of one end of the bolster, and Fig. 6 is a vertical section taken at the center of the bolster and the transom. Fig. 7 is a perspective view of another form of transom.

a is the upper arch-bar, constructed as a channel, with its flanges a'a'' extending downwardly. These flanges extend longitudinally of the bar, and there are also end flanges a''. The outer flange a' extends in a substantially straight line from end to end, while the inner flange a'' is divided by the lateral extensions a', which project to a considerable distance inwardly in order to afford the largest possible contact-surface with the transom. Between the members of the transom the arch-bar is reduced in width, as at a', in order to accommodate the bolster.

20 The lower arch-bar b has the opposite side flanges b', also extending downwardly, and this lower arch-bar is fitted within the side and end flanges of the upper arch-bar at their ends and the two riveted together and with the wear-plates or filling-blocks c, the latter being of substantially the depth of the flanges. The lower arch-bar is also widened out, so as to get the greatest increase of width at the transom, it having the lateral extensions b'' for this purpose.

25 By rigidly uniting the ends of the flanged arch-bars all tendency of these arch-bars to slip or slide longitudinally upon one another is corrected, as is also their tendency to lateral displacement.

30 The transom is composed of two channel-bars d d, having their webs vertical and their flanges standing away from one another. These transom-channels are riveted to the arch-bars and are provided with vertical embossments d' for increasing their strength and rigidity between the arch-bars. These embossments perform all the functions of the ordinary vertical columns which are used between the top and bottom arch-bars of the common diamond truck. The ends of the transoms may be boxed in, as in Fig. 7, for a purpose presently appearing.

35 The pedestal tie-bar or box-stay e is bolted to a filling piece or block f, which in turn is riveted to the lower arch-bar and to the flanges of the transom.

The spring-hangers g are riveted or otherwise secured to the transom.

40 The bolster is composed of a pair of channel-beams h h, having their webs vertical and their flanges extending toward one another. The bolster is of greatest depth at its center in order to meet the greatest strains, and its bottom tapers thence, preferably on curved lines, toward its ends, where it is of least cross-sectional area—that is to say, the bolster has a bellied conformation. Its ends are flat, so as to receive the springs or their caps or plates. Upon the upper flanges h' is riveted the center bearing-plate i, of any approved construction, and also upon these up-

per flanges are riveted or otherwise secured tie-plates j, in which are struck up the lower side bearings k. The lower portions of the channels h are bent upwardly from the center toward the ends, and in order to increase the strength the bottom flanges h'' are increased in width and converge, as indicated in Fig. 2, toward the end, and at the ends these flanges are united by an inner plate l and an outer plate l', both of which are riveted together and through the said flanges, so that these ends of the bolster are reinforced very stiffly and thus enabled to meet the strains imposed upon them in use. Internal stay-pieces m n are also used about midway between the ends of the bolster and adjacent to the king-bolt holes in order to reinforce the bolster at that point and thus equip the bolster to sustain the load. The stay-piece n may be constructed with the king-bolt hole n'. (See Figs. 4 and 6.)

45 The ends of the bolster are provided with embossments o to abut against the spring-hangers and prevent undue lateral or end-wise movement, and said ends are further provided with the inward projections p to pass the inner rivets by which the said spring-hangers are secured to the transom.

50 In the manner described the side frames, the transom, and the bolster are adapted to meet the ends of the invention hereinbefore specified, and the structure as a whole is of great strength and rigidity.

55 As already indicated, I prefer to construct the parts of my invention of steel plates pressed to shape, but do not limit my invention to that material.

60 In order to impart to the transom that flexibility necessary to enable the truck to adapt itself to variations in the track-surface, the said transom has a large portion of its webs cut away, as at d', Fig. 4, at points where such portions are not needed for strength, but where their absence may tend to enhance the flexibility of the structure.

65 As will be observed, the bolster is of variable depth, the greatest depth being at the center or in the plane of the transom and the least at the ends, and the object of this construction is to provide sufficient room for the springs without unduly increasing the height of the truck.

70 The reinforcing of the bolster at the ends enables the bolster to meet eccentric loads and imparts great stiffness, so as to withstand the strains brought to bear upon it by the springs upon which it rests. The inner reinforce l is carried far enough in toward the curved portion of the bottom flanges to be riveted to that curved portion and thus prevent any distortion of the flanges under eccentric loading.

75 In using flanged pressed-steel arch-bars I may employ thinner material and yet obtain equal, if not greater, strength than is possible by the use of ordinary rolled bars of rectangular cross-section.

By having the flanged ends of the arch-bars nested together and riveted the surface-contact is increased over the old rolled arch-bars and all danger of wear and consequent loosening of the fastenings is avoided.

It will be understood that the joined ends of the arch-bars, the box-stays, and the journal-boxes are united by the ordinary vertical bolts, the holes therefor being shown in Fig. 2.

10. The king-bolt hole n' in the stay-piece n is shown as flanged, and that is the preferred construction, because it gives a wider bearing for the king-bolt and one of greater endurance and support.

15. I have shown the transom-channels in Figs. 1, 2, 4, and 6 with open ends, but in Fig. 7 I show the end boxed in, as at d' . This latter construction has the advantage over the former in stiffening the transom at its ends,

20. thereby the better to support the bottom-arch-bar. Under some conditions this bottom arch-bar might have the downwardly-projecting flange at its outer face exposed to danger of breaking under overstraining in

25. case the car left the track or met with obstruction. In such event the bottom flange of the transom might yield and throw considerable strain at the lower edge of the flange of the arch-bar. The boxed-in end of the

30. transom would effectually correct this. The boxed-in ends serve, essentially, as struts in the side frames.

The invention is not limited to the manner of or means for boxing in the ends of the 35. transom.

What I claim is—

1. In a side frame of the diamond type of truck, the upper and lower arch-bars, made as channels of gradually-increasing width 40. from their ends toward the transom, having their flanges projecting downwardly, and their ends nested and riveted together, substantially as described.

2. In a side frame of the diamond type of 45. truck, upper and lower arch-bars made as channels, with their flanges projecting downwardly, and their ends nested and riveted together, substantially as described.

3. In a side frame of the diamond type of 50. truck, the pressed-steel upper and lower arch-bars, increasing in width from their ends toward their centers, their ends riveted together, and having intermediate lateral projections to which the transom is secured, substantially as described.

55. 4. In a side frame of the diamond type of truck, the pressed-steel upper and lower arch-bars, having downwardly-extending vertical flanges, ends riveted together, and intermediate lateral projections, combined with a channel transom, the flanges of which are riveted to the said arch-bars, substantially as described.

60. 5. In a side frame of the diamond type of truck, the separately-formed arch-bars, increasing in width from their ends toward their centers, cut away at their centers to

receive the bolster, and having their ends riveted together combined with a transom riveted to the said arch-bars, substantially 70. as described.

6. In a pressed-steel side frame for a truck of the diamond type, the upper and lower arch-bars, made as channels, and having their ends riveted together and thus rigidly united 75. wholly independently of other parts of the side frame, substantially as described.

7. In a side frame of the diamond type of truck, the upper and lower arch-bars, made as channels, having their ends nested together, 80. and rigidly united, and a filling-piece also rigidly secured in said ends, substantially as described.

8. In a pressed-steel side frame for a truck of the diamond type, the top and bottom 85. arch-bars made as independent channels and rigidly united at their ends by riveting such ends together, combined with a transom riveted to the said arch-bars, substantially as described.

9. The combination with the arch-bars, of a pair of channel bars or beams, constituting the transom, and with which the arch-bars are united, having vertical embossments d' 95. between the arch-bars, substantially as and for the purpose described.

10. A bolster, formed of a pair of channel-beams, the lower portions of which decrease in depth toward their ends, and whose flanges converge toward their ends, combined with 100. inner and outer tie-plates riveted to the said bottom flanges, the inner tie-plate extending over the bend of the flanges, substantially as and for the purpose described.

11. A side frame of the diamond type, composed of flanged arch-bars having their ends rigidly united, a box-stay, and a filling-piece 105. uniting the box-stay with the lower arch-bar, and all formed of pressed steel, substantially as described.

12. A truck-frame, composed of upper and lower arch-bars, formed as channels and having their ends nested and riveted together and thereby rigidly united, a transom composed of channels, and riveted to the arch-bars, a 115. box-stay and a filling-piece interposed between it and the lower arch-bar, and all constructed of pressed steel, substantially as described.

13. A pressed-steel bolster, having its lower 120. portion bellied, its ends of diminished cross-sectional area, its bottom flanges convergent at the ends, and said ends reinforced internally and externally by tie-plates, substantially as described.

14. A truck-frame, composed of upper and lower arch-bars, formed as channels, and having their ends rigidly united, and provided with lateral projections next the transom, a transom composed of channels and riveted to 130. the arch-bars, a box-stay and a filling-piece interposed between it and the lower arch-bar, and all constructed of pressed steel, substantially as described.

15. A transom, composed of channel-beams or channels having portions of their vertical webs removed, in order to increase the flexibility of the transom and give to the truck structure the greatest possible chance to adapt itself to variations in the track-surface, substantially as described.

In testimony whereof I have hereunto set my hand this 26th day of March, A. D. 1897.

AXEL S. VOGT.
